(57) CLAIM

The ornamental design for an industrial impact safety glove, as shown and described.

DESCRIPTION

FIG. 1 is a rear perspective view of an industrial impact safety glove in accordance with the present design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown are included for the purpose of illustrating a portion of the industrial impact safety glove and form no part of the claimed design.

The stippling in the drawings is for shading purposes only.
Although shown in the context of a right hand glove, an embodiment of the present invention also may be incorporated in a left hand glove.
